UNITED STATES PATENT OFFICE.

GEORGE WILLETT, OF CHICAGO, ILLINOIS.

MECHANICAL MOTOR.

SPECIFICATION forming part of Letters Patent No. 395,099, dated December 25, 1888.

Application filed September 16, 1887. Serial No. 249,889. (No model.)

To all whom it may concern:

Be it known that I, GEORGE WILLETT, a citizen of the United States, residing at Chicago, in the county of Cook and State of Illinois, have invented a certain new and useful Improvement in Mechanical Motors, which is fully set forth in the following specification, reference being had to the accompanying drawings, in which—

- 10 Figure 1 is a view illustrating my improved motor as applied to the propulsion of a boat; Fig. 2, a side elevation of the motor detached; Fig. 3, a plan view of the same; Fig. 4, a sectional view taken on the line 1 1 of Fig. 2, and looking in the direction of the arrow; Fig. 5, a rear elevation of one of the clutches and its carriage detached; Fig. 6, a detail sectional view of the same, taken on the line 2 2 of Fig. 4; and Fig. 7, a detail sectional view 20 taken on the line 3 3 of Fig. 3. Figs. 2 and 3 are on the same scale with respect to each other, but on a larger scale than Fig. 1, while Figs. 4 to 7, inclusive, are on the same scale with respect to each other, but on a still 25 larger scale than Figs. 2 and 3.

Like letters refer to like parts in all the figures of the drawings.

My invention relates to mechanical motors, and has for its object to provide an efficient 30 motor by means of which reciprocating motion may be converted into rotary motion.

I will now proceed to describe a construction in which I have practically carried out and applied my invention in one form, and 35 will then particularly point out in the claims those features which I deem to be new and desire to protect by Letters Patent. I will first, however, state that, although I have shown and will describe this one particular 40 application of the motor, I do so only for convenience in describing its construction and operation, as it will be understood that the same is of general application and may be used anywhere where a motor of its description 45 may be employed.

In the drawings, A represents a boat, (shown in dotted lines in Fig. 1,) B the propeller thereof, and C the propeller-shaft, which in the present instance is of course the shaft to 50 which a rotary motion is imparted by the motor. At its forward end the shaft C is pro-

vided with a gear-wheel, c, by means of which it is driven.

D represents a suitable base upon which the motor is mounted, this base being provided at each end with uprights d, which serve as a support for the various portions of the mechanism, as hereinafter described.

The shaft C has its forward bearing in the rear upright d. Upon each side of the base 60 D and parallel with the shaft C is arranged a spiral or screw, E, mounted to revolve in suitable bearings on the supports d. Preferably these bearings are constructed in the manner shown in detail in Fig. 7 of the drawings, in 65 which a screw, D', provided with a check-nut, d', extends through a suitably-threaded aperture in the upright d, its projecting unthreaded end d² entering a suitable socket or recess in the end of the spiral in a cylindrical hub, E', to which the end of the spiral is secured. By this means a bearing is provided which will resist the end-thrust of the spirals, and by means of which any wear may be readily taken up. The rear ends of the 70 spirals or their hubs E' at the rear end are each provided with a gear, e, the said gear meshing with the gear c on the shaft C. The spirals E are twisted in the same direction, or, in other words, are threaded alike. 80

The operating mechanism for the spirals is the same for each of them, and I will therefore describe the mechanism of one only, it being understood that the same description is applicable to the other. Parallel with the 85 axis of the spiral are arranged ways f, upon which is mounted a carriage, F, which travels upon the said ways. Each carriage is provided with an internal cylindrical chamber, within which fits a similarly-shaped nut, 90 G, which is retained by apertured end disks, F', secured to the body of the carriage. The nut G has an aperture, as shown at g, to receive the spiral E, which passes through the said aperture, and thus engages with the nut. 95 In order to reduce the friction, the aperture g is provided with rollers G', mounted on axes g', carried by the nut G. The rollers G' are arranged in the aperture g and are parallel with each other, the spiral E passing between 100 the said rollers, as shown more particularly in Fig. 4 of the drawings. The nut G is con-

nected to the carriage F by means of any suitable clutch mechanism which will permit the said nut to turn within the carriage in one direction, but will prevent its turning in the 5 opposite direction. Preferably I employ for this purpose a clutch mechanism which I have devised, and which is shown in the drawings. In this construction there are formed at diametrically-opposite points in the wall of the 10 chamber of the carriage F recesses f' , which receive rollers F², seated within the said recesses. Each recess is provided with an inclined wall, f^2 , extending toward the wall of the chamber in the manner shown in Fig. 4 15 of the drawings. The opposite wall, f^3 , of each recess f' is shaped to conform to the roller F², which is arranged within said recess, and the entire recess is at this point of such dimensions that the roller F² may rest 20 therein without being in contact or without binding against the periphery of the nut G. Two similar recesses, f^4 , are formed in the 25 wall of the chamber of the carriage F, in which recesses rollers F³ are mounted. The recesses f^4 are each provided with an inclined wall, f^5 , these walls having an opposite inclination to that of the walls f^2 , and each recess also has a wall, f^6 , conforming to the shape of the roller F³ within the said recess.

30 H indicates a band surrounding the bed of the carriage F and capable of movement around the said carriage within certain limits, being provided with a handle, H', by means of which it may be actuated. The band H is provided with pins h, extending radially inward through suitable slots, f^7 , in the nut G. These pins h extend into the corresponding recesses f' , on that side of the rollers F² therein on which the inclined walls f^2 are located.

35 The band H is also provided with similar pins, h', extending inward through slots f^8 into the recesses f^4 . The object of this band and its pins is to provide a reversing mechanism by means of which the entire operation of the 40 carriage may be at any time reversed by holding either the rollers F³ or the rollers F² in an inoperative position.

In the position of the parts shown in Fig. 4 45 of the drawings the pins h' bear against the rollers F³ and hold them against the wall f^6 of the recesses f^4 , in which position they are inoperative and have no contact with the periphery of the nut G. By moving the handle H' to the right the pins h on the band H may be caused to engage the rollers F² and hold them similarly in inoperative position, while at the same time the pins h' will be so moved as to release the rollers F³.

When the parts are in the position shown 50 in Fig. 4 of the drawings, it will be seen that the nut G may rotate freely in the carriage F in the direction indicated by the arrow, the rollers F² affording no resistance to such a movement, but turning freely within the recesses f' . Upon any movement of the nut G in the opposite direction, however, the rollers F² will immediately bind between the inclined

walls f^2 of the recesses f' and the periphery of the nut G, and will effectually lock the said nut and prevent its rotation. It will thus be 70 seen that the nut G may, as desired, be permitted to rotate freely in either direction, and at the same time be prevented from rotating in the opposite direction. The two carriages F are connected to each other by means of a 75 rope, cable, or chain, I, passing around suitable pulleys, i, arranged at the rear of the bed D. If desired, a similar rope, I', passing around pulleys i' at the front of the bed D, 80 may be employed to further connect the carriages F. Each carriage may be provided, if desired, with grooved wheels f⁹ to travel on the ways f. When the carriage is intended to be propelled by foot-power, which I prefer for this purpose, each carriage will be provided with a pivoted foot rest or pedal, J, supported between arms j, attached to the carriage, and a seat, J', for the operator will be arranged above and slightly in the rear of the motor. It will be understood, however, 85 that the motor may be also actuated by hand, if desired, or in any other suitable manner, to impart a reciprocating motion to the carriages F.

The apparatus thus organized operates in 90 the following manner: The operator upon the seat J' places his feet upon their respective pedals J and shoves forward first one carriage and then the other, thus imparting to the said carriages a simultaneous motion of 95 reciprocation in opposite directions. By reason of the connected ropes I and I' the forward motion of one carriage returns the other carriage to its original position. During the forward motion of the right-hand carriage F 100 the nut G carried by said carriage is prevented from rotating by means of the rollers F², and consequently imparts a movement of rotation to the spiral E, which is transmitted through the gear e of said spiral and the gear c on the shaft C to the said shaft, and consequently to the propeller B thereon. During 105 this forward movement of the right-hand carriage the left-hand carriage moves to the rear, and the nut G in said left-hand carriage is 110 free to rotate within the carriage, and thus permit the rearward movement thereof, it being understood, of course, that the motion imparted to the right-hand spiral E by the forward movement of the right-hand carriage 115 and its nut is also imparted to the left-hand spiral E, which renders it necessary that the nut in the said left-hand carriage should be free to rotate during the rearward movement of the carriage. The left-hand carriage F is 120 then moved forward, and, the nut G therein being locked and prevented from rotating by means of the rollers F², a movement of rotation is imparted to the left-hand spiral E, and thence through the gearing to the shaft C and propeller B thereof. During the forward movement of the left-hand carriage the right-hand carriage moves back and returns to its original 125 position, which is shown in the drawings.

It will thus be seen that the forward movement of each carriage imparts a movement of rotation to the corresponding spiral, which movement is transferred to the shaft C. It will also be observed that each nut is fixed during its forward movement and free to rotate during its return movement. The spirals G, being twisted in the same direction, impart a practically-continuous movement to the shaft C, and consequently to the propeller, whereby the boat is caused to advance in an obvious manner. When it is desired to reverse the action, or, in other words, to rotate the propeller in the opposite direction, the band H of each carriage is shifted over in the manner hereinbefore described, thus holding the rollers F² in inoperative position and causing the rollers F³ to operate. When the parts are in this position, the nuts are stationary during their rearward travel and free to rotate during their forward travel, so that obviously the direction of rotation of the spirals G, and consequently of the shaft C and propeller B, will be reversed. The employment of the rollers G' reduces the friction to a minimum, so that very little power is absorbed thereby. The speed may also be varied as desired by varying the relative size of the gears e and c, for it will be readily seen that relative speed of the shaft C and spirals E may be varied as desired by properly proportioning the gearing and connecting the same. The connecting ropes or cables insure simultaneous operation of the carriages and cause them both to be actuated by the forward thrust applied to one of them only.

Behind each of the rollers F² and F³ is arranged a spring, f¹⁰, which tends to force the rollers toward the inclines f² and f³, respectively, in order to cause them to engage with the said inclines to quickly obtain a reversal of the movement of the parts.

It is obvious that, although I have shown my improved motor as applied to the propulsion of a boat and as adapted to be actuated by foot-power, it is not limited to this particular application or mode of actuating. It may be employed in any situation where it is desired to convert reciprocating into rotary motion, and reciprocation may be imparted to the carriages by any suitable means. Moreover, two or more of these motors may be employed at the same time, the shaft C being sufficiently extended for that purpose and being provided with the necessary gearing. I am enabled to employ two or more motors in this manner, for the reason that the operation of each motor is entirely independent of the operation of the others, the spirals and their nuts being free to turn in the carriages when driven from the shaft C.

Various modifications in the details of construction may also be made. For instance, instead of placing the upper wheels, f⁹, above the upper ways, f, as shown in the drawings, I may, and in some cases prefer to, place the said wheels below the same. These wheels

may, however, be entirely dispensed with, the carriages being in that case provided with sleeves or equivalent devices which embrace or fit upon the ways to hold the carriages in place. I therefore do not wish to be understood as limiting myself to the precise details hereinbefore described, and shown in the drawings.

Having described my invention, what I claim as new, and desire to secure by Letters Patent, is—

1. The combination, with the shaft, of spirals connected thereto by suitable gearing and a reciprocating carriage for each spiral, provided with a rotatable nut through which the spiral passes, and which is connected to the carriage by a suitable clutch mechanism, substantially as and for the purposes specified.

2. The combination, with the shaft, of spirals on each side thereof parallel with the same and connected thereto by suitable gearing, a reciprocating carriage for each spiral, and a rotatable nut mounted in each of said carriages, connected thereto by suitable clutch mechanism, and engaging the spirals to rotate the same, substantially as and for the purposes specified.

3. The combination, with the shaft C, having gear c, of the spirals E, provided with gears e to mesh with the gear c, the reciprocating carriages F, one for each spiral, a nut mounted in each carriage and connected thereto by a suitable clutch mechanism and engaging with the spiral, and a rope or cable passing around suitable pulleys and connecting the two carriages, substantially as and for the purposes specified.

4. The combination, with the shaft C, of the spirals E, connected thereto by suitable gearing, the carriages F, one for each spiral, each provided with a nut, G, connected thereto by suitable clutch mechanism and engaging the spirals, foot-rests J, mounted on the carriages, and a seat, J', arranged above and in the rear of the spirals, substantially as and for the purposes specified.

5. In a device for converting motion, the combination, with the shaft, of the spiral mounted to revolve in suitable bearings and connected to the shaft by suitable gearing, the reciprocating carriage, the nut mounted in said carriage and connected thereto by suitable clutch mechanism, said nut being provided with a central aperture through which the spiral passes, and rollers mounted in said aperture and bearing upon the spiral, substantially as and for the purposes specified.

6. The combination, with the shaft, of the spirals connected thereto by suitable gearing, a reciprocating carriage for each spiral, and a rotatable nut mounted in each carriage, provided with an aperture through which the corresponding spiral passes, and connected to the carriage by a reversible clutch mechanism, substantially as and for the purposes specified.

7. In a device for converting motion, the combination, with the spiral E, of the rotatable nut G, provided with a central aperture through which said spiral passes, the carriage 5 F, reciprocating in the line of the axis of said spiral and provided with a cylindrical chamber to receive the nut G, said carriage being provided in the wall of said chamber with recesses f^2 and f^4 , having oppositely-inclined 10 walls f^2 and f^5 , the rollers F² and F³, arranged,

respectively, in said recesses, and the band H, provided with pins h and h', extending into said recesses, the said band being movable in order to hold either the rollers F² or F³ in inoperative position, substantially as and for 15 the purposes specified.

GEORGE WILLETT.
